V. R. WILL,
DIRECTION SIGNAL FOR MOTOR VEHICLES,
APPLICATION FILED OCT. 1, 1917.

Patented Oct. 8, 1918.

INVENTOR,
Victor R. Will
BY
Berry S. Webster
ATTORNEY.

UNITED STATES PATENT OFFICE.

VICTOR R. WILL, OF SACRAMENTO, CALIFORNIA.

DIRECTION-SIGNAL FOR MOTOR-VEHICLES.

1,280,925.

Specification of Letters Patent.

Patented Oct. 8, 1918.

Application filed October 1, 1917. Serial No. 194,131.

To all whom it may concern:

Be it known that I, VICTOR R. WILL, a citizen of the United States, residing at Sacramento, in the county of Sacramento, State 5 of California, have invented certain new and useful Improvements in Direction-Signals for Motor-Vehicles; and I do declare the following to be a full, clear, and exact description of the same, reference being had to the 10 accompanying drawings, and to the characters of reference marked thereon, which form a part of this specification.

This invention relates to improvements in signals for use on motor vehicles to indicate 15 when the driver of the vehicle is about to turn the same or to come to a stop. Traffic, especially in large cities, is becoming more and more congested, and very many accidents are occurring due to the lack of signaling facilities to indicate the movements 20 of the vehicles. Ordinances have been enacted, requiring the extension of the hand when the vehicle is about to turn or stop, but this at its best is a very poor method 25 and in closed cars is an impossibility. I aim therefore, to produce a signal of simple construction located at or near the driver's seat and which can, by simple movement of the hand, be extended or retracted. When 30 extended, the air currents which are constantly present when the vehicle is moving, will revolve the signal, which can be of a bright color or colors. For night driving, I provide a flash light effect, which causes 35 the signal to be even more discernible at night than in the day time.

The advantages of this will be obvious to those skilled in the art.

A further object of the invention is to produce 40 a simple and inexpensive device and yet one which will be exceeding effective for the purposes for which it is designed.

These objects I accomplish by means of such structure and relative arrangement of 45 parts as will fully appear by a perusal of the following specification and claims.

In the drawings similar characters of reference indicate corresponding parts in the several views.

50 Figure 1 is a perspective view of the signal showing also a dotted outline of a portion of the vehicle to indicate the position of the signal thereon.

Fig. 2 is a diagrammatic outline of the 55 electrical wiring connected with the signal.

Fig. 3 is an end view of the signal partly

broken out and in section to show the electrical wiring therein.

Referring now more particularly to the characters of reference on the drawings, the 60 numeral 1 designates a slotted guide plate of any suitable material fastened to the vehicle at any desired point, but preferably at the base of the windshield and in front of the driver's seat. This guide terminates in 65 an inclosed hood or box 2 on the back face of which is a mirror 3. Slidable within the guide 1 and projecting into the box 2 is the signal arm 4 which has a small operating handle 5 at its inner end. In the outer end 70 of the arm 4 is journaled a revolving pin 6. On one end of the pin 6 are a pair of blades 7 bent slightly at an angle to the direction of travel of the vehicle. On the opposite end of the pin 6 are a pair of blades 8 which 75 are interposed substantially in alinement with the space between the blades 7. Interposed on the arm 4 between the blades 7 and 8 is an electric lamp 9. One wire 10 leads from this lamp to the ground at any suitable 80 point, the other wire 10^a from such lamp extends through the arm 4 and connects with a switch blade 12, which, when the signal is extended, contacts with another switch blade 13 mounted on the guide 1. From this blade 85 13 a wire 14 leads to a switch 11 which may be connected with either a stationary battery 15 or with a magneto 16 by means of wires 17 or 18, respectively. Said battery and said magneto are, of course, mounted 90 in the usual manner.

In practice in the day time the switch 11 is positioned so as to leave an open circuit from either the magneto or the battery. When the operator is about to turn or stop 95 he grasps the operating handle 5 and projects the arm 4 which carries the signal 7-8 out of the box 2 into view of the traffic in front or behind. The air currents occasioned by the movement of the vehicle act 100 against the blades 7-8 to revolve the signal, this being made of bright material. This revolving action quickly directs the attention of the traffic on the street which can then take care not to collide with the vehicle. 105 When not in use the signal is retracted into the box 2. The mirror 3 aids the operator of the vehicle in determining the necessity of extending the signal.

At night the switch 11 is closed to connect 110 either the battery 15 or magneto 16 with the lamp circuit. Thus when the arm 4 is ex-

tended, the switch blade 12 comes in contact with the blade 13 and completes the circuit through the lamp 9 and lights the same. Then as the signal 7—8 revolves, the blades 5 7 and 8 alternately move in front of and away from the lamp, causing it to give a flashing light which is readily discernible to the traffic.

From the foregoing description it will be 10 readily seen that I have produced such a device as substantially fulfills the object of the invention as set forth herein.

While this specification sets forth in detail the present and preferred construction of 15 the device, still in practice such deviations from such detail may be resorted to as do not form a departure from the invention, as defined by the appended claims.

Having thus described my invention what 20 I claim as new and useful and desire to secure by Letters Patent is:

1. A signal for motor vehicles comprising a slotted guide terminating in an inclosed member, an arm slideable in the guide, a signal member on the arm, said signal member 25

comprising a set of revolving blades adapted to be actuated by the air currents occasioned by the forward movement of the vehicle and a lamp interposed between the blades and adapted to be lighted when the signal is projected whereby the revolving blades will cause the light from the lamp to throw off intermittent flashes.

2. A direction signal for motor vehicles 35 providing an arm arranged to be projected from the vehicle, a revolving pin on the outer end of the arm, a pair of blades fixed at each end of the pin, those blades at one end being set at right angles with respect to the others.

3. A direction signal for motor vehicles 40 providing an arm arranged to be projected from the vehicle, a revolving pin on the outer end of the arm, a pair of blades fixed at each end of the pin, those blades at one end being set at right angles with the others, a lamp interposed on the arm between the blades.

In testimony whereof I affix my signature.

VICTOR R. WILL.
